(57) **CLAIM**

I claim the ornamental design for a remotely-controlled power cutoff switch, as shown and described.

DESCRIPTION

FIG. 1 is a perspective view of the front of a remotely-controlled power cutoff switch.

FIG. 2 is a perspective view of the back thereof.

FIG. 3 is a left side view thereof.

FIG. 4 is a front view thereof.

FIG. 5 is a back view thereof.

FIG. 6 is a top view thereof; and,

FIG. 7 is a bottom view thereof.

The right side view is the mirror image of the left side view (FIG. 3) as the switch is symmetric.
